ADAPTING SHEET METAL ELEMENTS FOR SCREWS

Bion C. Place, Detroit, Mich., assignor to Prestole Devices, Inc., Detroit, Mich., a corporation of Michigan

Application April 16, 1938, Serial No. 202,560

4 Claims. (Cl. 85—32)

The present invention involves the preparation of sheet metal structures or elements for threaded engagement by screws. More particularly, the invention is concerned with a method and arrangement for adapting sheet metal to provide a self-locking thread from the portion of the metal immediately adjacent the wall of the opening therein through which the screw passes without rendering the sheet metal structure previous to moisture or the like.

The present invention constitutes an improvement upon that of the patent previously granted to me on May 18, 1937, Patent No. 2,081,065. Sheet metal elements adapted for the reception of a screw in the manner described in said patent are generally entirely satisfactory. Under some circumstances, however, the slit that radiates from the opening through which the screw passes is objectionable in that moisture, dirt or undesirable matter can pass through the sheet metal element at the slit formed therein. Accordingly, when the invention of said patent is applied in situations in which the sheet metal element is relied upon to prevent the passage of foreign substances therethrough, said slit becomes objectionable.

It has been further found that when heavy pressure is exerted against the top of the cone, by means of a screw having a strong thread, that, occasionally, the two edges of the radially extending slit are caused to pass each other thus distorting the shape of the opening in the top of the protuberance so that the sheet metal does not grip the base of the thread of the screw substantially uniformly around the circumference of the screw, as is most desirable for efficient self-locking action upon the screw.

The primary purpose of the present invention is to provide a generally conical protuberance having an opening in the top thereof shaped to provide a single thread for a screw, in which the high and low points of the single thread are obtained by offsetting a portion of the protuberance to form an upstanding radial web rather than by slitting the same.

A further object of the invention is to provide sheet metal structures with a self-locking thread formed by bossing the metal adjacent the screw receiving opening therein so that a substantially complete thread is provided by the wall of each opening without slitting the protuberance formed by the bossing, except only to the depth of the thread of the screw for which the sheet metal structure is adapted.

Another object of the invention is to provide

an improved method of adapting a sheet metal structure for the reception of a screw including the formation of a protuberance in the metal surrounding the opening for the screw, and the offsetting of the metal of the protuberance to form an integral web between the high and low points of a thread provided by the wall of the opening.

Still another object of the invention is to adapt a sheet metal structure for the reception of a screw by forming a protuberance therein, containing the screw receiving opening, which protuberance is provided with a radial offset presenting a substantial vertically extending wall or web to the thread of the screw, which wall or web may be perforated by the thread to the extent necessary to permit threaded engagement by the screw, said offset web otherwise thus presenting an imperforate wall.

Still another object of the invention is to provide a sheet metal structure with a protuberance having a screw receiving opening in the top thereof which possesses great resistance against forces tending to flatten it, and which, when partially flattened, is certain to substantially evenly grip the shank of the screw at the base of the thread engaged therewith throughout substantially the entire circumference of said shank.

Still another object of the invention is to provide an improved method of providing a threaded engagement between a sheet metal structure and a screw consisting of embossing the metal around the screw opening, forming an offset web radiating from the opening in the embossment, and then causing the thread of the screw to itself cut its passage through the web provided by said offset, whereby the screw is engaged with said structure with a minimum perforation of the structure.

Still further objects of the invention will appear as the description thereof proceeds with reference to the accompanying drawing in which:

Figure 1 is a side elevational view of a fragment of a sheet metal structure or element adapted for the reception of a screw in accordance with the present invention;

Figure 2 is a plan view of the fragment illustrated in Figure 1;

Figures 3 and 4 are respectively sectional views taken on the plane indicated by the lines 3—3 and 4—4 of Figure 2;

Figure 5 is a sectional view showing the sheet metal element or structure secured to a further sheet metal structure by means of a screw, the screw being shown prior to tightening thereof;

Figure 6 is a view corresponding to Figure 5, but showing the screw drawn taut to produce a locking between the screw and the sheet metal structure or element;

5 Figure 7 is a plan view of a sheet metal nut adapted for the reception of a screw in accordance with the present invention; and

Figure 8 is a sectional view taken on the plane indicated by the line 8—8 in Figure 7.

10 Like reference characters indicate like parts throughout the several figures.

Numeral 10 designates a fragment of a sheet metal element or structure provided with a generally conical protuberance 11 having an opening 12 in the top thereof. The wall 13 of the opening 12 is shaped to provide a single helical thread having a pitch corresponding substantially to the pitch of a screw which is to be engaged with the structure or element. An offset web 14 extends 20 radially of the protuberance, said offset web having its maximum height adjacent the opening and diminishing in height toward the base of the protuberance where it disappears in the plane of the metal structure or element, as illustrated. 25 The offset web provides the high point 15 (Figure 4) of the single thread provided by the edge of the opening and the low point 16 of said thread.

The protuberance has a base that is wide compared to the diameter of the opening in the top 30 thereof, the width of the protuberance at its base preferably exceeding twice the diameter of said opening. Said diameter corresponds approximately to the diameter of the screw intended to be threaded into said opening at the base of the 35 thread thereof. The protuberance is also made relatively deep, the preferred arrangement involving a protuberance having its lowest point 16 spaced above the adjacent structure a distance at least equal to the pitch of the screw to be 40 engaged therewith for the purpose hereinafter to be referred to.

Preferably the protuberance 11 has a base merging into the plane of the structure or element on a smooth curve 17, that is concave as 45 seen from the top of the element or structure. Adjacent the top of the protuberance the metal is preferably curved inwardly on a smooth curve 18, that is convex as seen from the top of the protuberance so that the wall 13 of the opening 50 12 is disposed normal, or substantially normal, to the plane of the element or structure 10. Inasmuch as it has been found that a protuberance having the concavo-convex form just referred to 55 possesses the greatest strength against pressures applied to the top thereof by the action of the screw, and exerts, when flattened, the most effective gripping pressure against the shank of the screw, protuberances having this form are preferred. However, it should be understood that 60 the scope of the present invention contemplates the utilization of any protuberance designated as generally conical. Also, protuberances shaped so that the wall of the opening extends at an acute angle to a plane normal to the metal element or structure are within the purview of the present 65 invention.

Sheet metal elements or structures may be provided with protuberances such as just described either in a single stamping operation, or in multiplicity of stamping operations, as may be preferred. Preferably, they are formed in a single stamping and punching operation, the opening being first formed in the sheet metal element or structure and then the metal surrounding said 75 opening brought into the shape already described

by pressure between mating dies. When the protuberance has been completed, the opening 12 is preferably circular. While some drawing or stretching of the metal is necessary to form the described protuberance, it has been found that 5 sheet metal will successfully withstand such stretching without rupture. The point of maximum stretching of the metal is at the point of formation of the offset web 14 and, preferably, the protuberance is formed without rupturing the 10 metal at this point. If desired, however, the protuberance may be formed so that the edge of the offset web is ruptured or weakened to facilitate the threading of the screw through the sheet metal structure in the manner presently to be 15 referred to.

The manner in which a sheet metal element or structure, such as that just described, is used is made clear by Figures 5 and 6 of the drawing. The sheet metal element or structure 10 is there 20 shown disposed upon another structure 19, to which it is to be secured by means of a screw 20, having a head 21 provided with a screw driver slot 22 or any other means for turning the screw. The thread 23 of the shank of the screw 20 is 25 made of sufficient width so that when the shank of the screw is passed through an opening 24 in structure 19 and turned to the opening 12 in the sheet metal element or structure 10, the thread 30 will substantially overlap the top of the conical 35 protuberance. Preferably, the pitch of the screw 23 substantially exceeds the thickness of the metal of the element or structure 10 so that the edge of the opening 12 therein which forms the 40 thread may freely enter between adjacent convolutions of the thread as clearly shown in the drawing.

When a protuberance having an unperforated or unweakened offset wall web is used, the screw 45 is relied upon to itself cut the small notch corresponding to the cross section of the thread in the substantially vertically extending edge of said offset web. The shallow notch formed by threading the screw through the edge of the offset web is designated by 25 in Figure 5. Of course, if 50 said edge is weakened or ruptured during the operation of forming the protuberance having an offset web, less force is required in threading the screw through the protuberance, the thread of the screw being then relied upon merely to enlarge or shape the weakened portion of said offset web as the screw is threaded through the protuberance.

The position of the screw after the head 21 55 thereof contacts with the outer surface of the structure 19 is illustrated in Figure 5. In this position the screw could be readily removed from engagement with the element or structure 10 by a reverse rotation thereof, no substantial locking action being then present. In order to produce a firm locking engagement between the element 10 and the shank of the screw 20, the screw is turned through approximately one further revolution. Said further rotation of the screw exerts a substantial pressure against the 60 top of the protuberance causing a substantial flattening thereof as illustrated in Figure 6. As the protuberance is flattened, the opening 12 is constricted in size resulting in a firm frictional engagement between the wall of said opening and the shank of the screw at the base of the thread. Inasmuch as the protuberance is unweakened by any radial slit extending from the opening in the 65 top thereof, the size of the opening is reduced uniformly, the protuberance being of substan- 70 75

tially the same strength at every point radially outwardly of the screw. An unusually effective self-locking action is thus provided between the protuberance and the screw preventing reverse 5 rotation of the screw when this invention is utilized in connection with structures subject to vibration.

It is to be understood that in the final position of the screw, an effective seal is provided between the screw and the opening in the flattened protuberance, because of the uniform engagement of the wall of the opening with the shank of the screw at the base of the thread and because the offset is cut only to the extent necessary to permit the passage of the thread through the edge thereof.

Figures 7 and 8 illustrate the application of the invention of Figures 1 to 6, inclusive, to a sheet metal nut 26. The body of said nut is provided with a generally conical protuberance 27 having an opening 28 in the top thereof, and a radially extending offset wall or web 29, corresponding to the generally conical protuberance already above described. The wall of the opening 28 is shaped to provide a single helical thread. A multiplicity of slits 30 extend inwardly of the periphery of the nut 26 and one or both of the edges provided by said slits are bent downwardly providing teeth 31. While nut 26 is shown circular in form it will be understood that it may be made rectangular, hexagonal or in any other desired shape.

In the use of such a nut as illustrated in Figures 7 and 8, the shank of the bolt is threaded through the opening 28 therein in the manner already described, and rotation of the bolt is continued until it causes a substantial flattening of the protuberance. In flattening said protuberance a substantial pressure is applied causing the teeth 31 to bite into the structure against which the nut abuts, preventing rotation of the nut with respect to said structure. A locking action between the nut and the bolt is also caused by the flattening of the protuberance in the manner already described, so that relative rotation between the bolt and the nut, and between the nut and the structure against which it abuts are prevented. In this way a self-locking nut, not likely to become disengaged from the bolt, is provided.

The invention may be embodied in other specific forms without departing from the spirit or essential characteristics thereof. The present embodiment is therefor to be considered in all

respects as illustrative and not restrictive, the scope of the invention being indicated by the appended claims rather than by the foregoing description, and all changes which come within the meaning and range of equivalency of the claims are therefore intended to be embraced therein.

What is claimed and desired to be secured by United States Letters Patent is:

1. A sheet metal structure designed for self-locking threaded engagement by a screw, comprising a protuberance in the sheet metal having an opening in the top thereof, said protuberance being shaped to cause the greater portion of the wall of said opening to present a substantially complete single helical thread for engagement by said screw and to cause the remainder of said wall to extend sharply away from the plane of the sheet metal surrounding said protuberance in the form of a radial web, the protuberance merging gradually without perforation in every direction from said wall into said plane.

2. A sheet metal structure designed for self-locking threaded engagement by a screw comprising a protuberance extending substantially above the surface plane of said structure, an opening for the passage of said screw in the top of said protuberance, the wall of said opening being continuous and providing a single helical thread the high and low points of which are interconnected by a radial web resulting from offsetting the metal of the protuberance.

3. The method of adapting a sheet metal structure for the reception of a screw, which consists in pressing a protuberance in the metal, then forming an opening in the center of the protuberance, then shaping the wall of said opening to form a helical thread, and providing an offset web in the metal of the protuberance adjacent said opening between the high and low points of said thread.

4. A sheet metal structure designed for self-locking threaded engagement by a screw, comprising a generally conical protuberance having an opening at its top, an offset web in said protuberance radiating from said opening, the wall of said opening being in the form of a helix beginning and ending adjacent said offset web and presenting a thread to said screw that is spaced at its lowest point a substantial distance above the adjacent structure, the thickness of said metal being substantially less than the pitch of said helix.
